UNITED STATES PATENT OFFICE.

FREIDA RAUTZENBURG, OF PHILADELPHIA, PENNSYLVANIA.

SOAP-RECEPΤΑCLE.

1,211,353.

Specification of Letters Patent.

Patented Jan. 2, 1917.

Application filed April 6, 1916. Serial No. 89,393.

To all whom it may concern:

Be it known that I, FREIDA RAUTZENBURG, a citizen of the United States, residing at Philadelphia, in the county of Philadelphia and State of Pennsylvania, have invented new and useful Improvements in Soap-Receptacles, of which the following is a specification.

This invention relates to soap receptacles for household and toilet use.

The chief characteristic of this invention resides in the provision of a device of this character having means for positively delivering the soap from the receptacle when desired, and means operable with the first mentioned means for loosening the soap within the receptacle, whereby the delivery of the soap from the receptacle will be insured.

Another object of this invention is to provide a device of this character having means for draining the water from the cake of soap so that the liability of the soap adhering to the walls of the receptacle will be minimized.

Another object of this invention is to provide a device of this character having a perforated hinged lid for the receptacle, the lid serving as a soap tray when using the soap for short intervals.

Another object of this invention is to provide a soap receptacle which contains the desirable features of simplicity, durability and efficiency and which is so constructed as to permit the easy cleaning of the same.

Other objects of the invention will appear as the specification is read in connection with the accompanying drawings, in which;

Figure 1 is a perspective view with the lid raised showing my device constructed in accordance with my invention. Fig. 2 is a bottom plan view. Fig. 3 is a transverse vertical section showing the soap panel in normal position. Fig. 4 is a transverse vertical section showing the soap panel in delivery position. Fig. 5 is a perspective detail view of the soap panel. Fig. 6 is a perspective detail view of the soap elevating U-shaped member.

Referring to the drawings in detail, I des-

ignates a supporting plate which is formed of metal and which is preferably rectangular in configuration, the same being provided adjacent its upper edge with eyes 2 which are adapted to receive nails or the like whereby the plate may be supported upon a wall. Secured to the front face of the plate are the free extremities of the substantially U-shaped casing 3, the free ends of the casing being provided with suitable extensions which are adapted to pass through the plate 1 to hold the casing and plate in assembled position as will be understood. The casing 3 is preferably beaded upon its upper and lower edges so as to reinforce the same and present a rigid structure.

Connecting the parallel portions at their confronting faces and adjacent the supporting plate 1 is a horizontal rod 4, the opposite extremities of which extend through the parallel portions of the casing and are then spread to securely retain the rod within the casing. Pivotaly mounted upon the rod 4 by means of the alined ears 5 is a panel 6, the same serving to form the bottom wall of the casing and of an area slightly less than that of the interior of the casing. It will be noted that the ears 5 formed in the panel 6 depend from the under side thereof, the two end ears being formed integral with the panel while the middle ear is downstruck from the panel as is clearly shown in the drawing. The panel 6 is adapted to support a cake of soap thereupon and has its opposite edges provided with upstanding flanges 7, the flanges serving to prevent the soap from sticking to the sides of the casing.

Mounted upon the rod 4 adjacent its opposite extremities and lying within the casing 3 are a pair of coiled springs 8 the outer extremities of which are bent downwardly and rearwardly into the supporting panel 1, the inner extremities 10 extending laterally from the rod 4 and engaging the under side of the panel 6. These springs 8 exert their tension upon the panel 6 to hold the same in horizontal position within the casing 3, the panel 6 being provided at its opposite ends with depending handles 11, the handles be-

ing bent at right angles and engaging the lower edge of the casing to limit the upward movement of the panel as will be understood. Swingly mounted on the rod 4 at 5 a point medially thereof is a substantially U-shaped member 12, the horizontal portions of the member being provided with slined openings which are adapted to receive the rod as is clearly shown in the drawings. 10 The horizontal portion 13 of the member 12 is arranged on an incline and is adapted to contact with the supporting plate 1 to limit the downward movemnt of the member as will be hereinafter described. The parallel 15 portions of the member 12 have their upper edges inclined downwardly from their connection with the horizontal portions to the outer ends, while the lower edge of one of these parallel portions is provided with a depression 15 which is adapted to receive an extension 16 formed on the adjacent end of one of the springs 8. This extension 16 is adapted to normally hold the member 12 in horizontal position within the casing. 20 The panel 6 is provided with transversely extending slots 17 arranged in parallel relation and are adapted to receive the parallel portions of the member 12 as is clearly shown in Fig. 4 of the drawings. It will be 25 seen from this construction that when the panel 6 is swung downwardly upon the rod 4 by gripping one of the handles 11 and exerting pressure downwardly against the tension of the coil springs, the member 12 will 30 move downwardly with the panel for a certain distance until the horizontal member 13 thereof engages the face of the supporting plate 1, whereupon the parallel portions of the member will extend through the slots 17 35 to engage a cake of soap as will be herein-after described. In order to prevent lateral movement of the member 12 upon the rod 4, I have mounted on the rod 4 between the parallel portions of the member, a pair of 40 sleeves 18, the inner ends of the sleeves engaging the sides of the middle ear 5, while the outer ends abut the inner faces of the parallel portions and prevent lateral movement of the member as previously stated. 45 Pivotaly mounted upon the supporting plate 1 and adapted to close the top of the casing, is a soap tray 19. This tray 19 has its major central portion depressed as at 50 from the flanges 21, the flanges being adapt- 55 ed to engage the upper edge of the casing and limiting the downward movement of the tray. The depressed portion 20 of the tray is adapted to hold a cake of soap, when using the cake of soap for short intervals and 60 eliminating the necessity of placing the soap within the casing each time the user is finished with the soap. To permit the water to thoroughly drain from the cake of soap while lying within the tray 19, I have

formed the depressed portion of the tray 25 with a series of perforations 22.

Having described the construction of my device, I will now describe the operation and the easy manner in which the soap may be delivered from the receptacle. Upon lifting 70 the lid or tray 19, the cake of soap is placed within the casing so as to lie upon the panel 6. In the event that the soap is saturated with water, the water will drain through the slots 17 formed in the panel and also 75 down between the edges of the panel and the inner face of the casing. I have previously stated that the panel was of a slightly less area than the internal area of the casing. When it is desired to deliver the cake of soap 80 from the receptacle, by pressing downwardly upon one of the handles 11, the panel will be swung downwardly upon its pivot whereupon, the parallel portions of the member 12 will be projected through 85 these slots 17 to elevate the cake of soap from the panel. Owing to the inclined upper edges of the parallel portions, the cake of soap will be precipitated out of the receptacle as will be understood. In providing 90 the panel 6 with the member 12, I prevent the cake of soap from sticking to the upper face of the panel and thereby insure the proper delivery of the soap from the receptacle. The cake of soap having been 95 removed and the panel having been relieved of its downward pressure, the coil springs will exert their tension to return the panel to its normal position within the casing.

It is thought from the foregoing taken in 100 connection with the accompanying drawings that the construction and operation of my device will be apparent to those skilled in the art without further description, and that minor changes in size, shape, proportion and minor details of construction may 105 be made without departing from the spirit and scope of the appended claims.

What I claim is:

1. A device of the class described comprising a casing having a panel pivotally mounted for downward swinging movement, means for holding the panel in horizontal position within the casing, and a means co-operating with said panel for removing the soap from the panel and delivering the soap from the receptacle when the panel is swung downwardly.

2. A device of the class described comprising a casing having a panel mounted 120 for swinging movement, means co-operating with said panel for removing the soap from the panel and delivering the same from the receptacle when the panel is swung, and means for returning said panel and the last 125 mentioned means to normal position.

3. A device of the class described comprising a casing, a rod mounted within the

casing, a panel swingingly mounted upon said rod, said panel being provided with slots, a substantially U-shaped member swingingly mounted upon said rod and having the parallel portions thereof disposed within the slots of said panel, springs mounted on said rod and engaging said panel to hold the same in horizontal position, and an extension formed on one of said

5 springs and engaging said U-shaped member to normally hold the parallel portions thereof within said slots.

In testimony whereof I affix my signature in presence of two witnesses.

FREIDA RAUTZENBURG.
